L. K. ENGLE

FASTENING AND SUPPORTING DEVICE

Filed Oct. 11, 1927

INVENTOR:
LILLIAN K. ENGLE,
BY
Medenshaw & Gumbank,
ATTORNEYS.

UNITED STATES PATENT OFFICE.

LILLIAN K. ENGLE, OF LANSDOWNE, PENNSYLVANIA.

FASTENING AND SUPPORTING DEVICE.

Application filed October 11, 1927. Serial No. 225,583.

My invention relates to a new and useful fastening and supporting device and more particularly to a device of this character which can be firmly and detachably secured 5 to fasten and support different objects to each other or to a support without the aid of any external or auxiliary means.

My invention further relates to a fastening and supporting device which may be employed in the vertical, horizontal or pendant position, that is, one which is adapted to resist lateral, downward and upward strain or pull.

My invention further relates to a novel 15 device of this character wherein the piercing or fastening elements are integral with the supporting or retaining element, the entire device being made of suitable sheet metal or the like, by a single stamping, punching or 20 casting operation.

To the above ends, my invention consists of a double hook, piercing arms or prongs on either side of said hook, a base common to 25 said hook and said prongs and forming a right angle therewith, and a pair of doubled piercing arms integral with and extending from either end of the opposite edge of said base in parallelism therewith, said prongs and doubled arms being provided with novel 30 means for interlocking with the fabric or other material, said elements being also provided with bottom grooves forming stiffening 35 ribs.

My invention further consists in so 40 constructing the piercing arms and prongs above referred to, as to afford a firm, detachable engagement with the object being fastened or supported, and to reduce the holes or perforations made by said prongs and arms to a minimum.

My invention further consists in providing the prongs and base above referred to with reinforcing ribs to adapt my novel device for heavy duty without materially increasing 45 the weight or dimensions thereof.

My invention further consists in various other features of construction and collocation of parts as hereinafter described.

For the purpose of illustrating my invention, I have shown in the accompanying drawings, forms thereof which are at present preferred by me, since they will give, in

practice, satisfactory and reliable results, although it is to be understood that the various instrumentalities of which my invention consists can be variously arranged and organized and that my invention is not limited to the precise arrangement and organization of these instrumentalities as herein shown and described.

In the accompanying drawings,

Fig. 1 represents a view in side elevation showing my fastening and supporting device fastened to and supporting a curtain or similar object.

Fig. 2 represents a plan view of my novel device shown detached.

Fig. 3 represents a bottom view of the same.

Fig. 4 represents an end view of the same.

Fig. 5 represents a section on line 5—5 of Fig. 2.

Fig. 6 represents a plan view of a modified construction embodying my invention.

Fig. 7 represents an end view of a further modified form embodying my invention.

Referring to the drawings, in which like reference characters indicate like parts, 1 designates a fastening and supporting device embodying my invention comprising the 25 relatively long, slightly converging, pointed, tapering prongs 2, the relatively short, pointed, oppositely disposed, doubled arms 3, and the intermediate, integral base or connecting body portion 4. From the base 4 and integral therewith, extends the arm or tongue 5 having the humped portion 6, said arm being bent back upon itself to form the hook 7 and being continued rearwardly to form the arm 8 which is similarly humped as at 9, 30 the humps 6 and 9 on the arms 5 and 8 respectively forming a lock or closure for the doubled hook or retaining member 7, as will be understood from Figs. 1, 2, 3, 4 and 5.

The tapering, piercing prongs 2 and 3 are 35 provided with the recessed portions 10 which serve to interlock with the weave or warp and weft of a textile fabric such as a curtain or other material into which they may be inserted. Another advantage of the recessed portions 10 is that when the material is initially pierced by the prongs 2 and arms 3, a hole or opening is made, large enough to 40 permit of the passage of the widest portions

11 of said prongs and arms, and if the material is permanently thus distended, when the prongs and arms are withdrawn, a relatively large hole or opening remains, since the warp and weft of the material having been widely parted over a long period of time, fail to resume their normal positions, due to the loss of elasticity. By providing the recessed portions 10, however, the fabric, and particularly the warp and weft of the fabric, not having lost their inherent elasticity, will tend to resume their normal positions around the recessed portions 10 and being thus not widely parted or distended, only a small hole 15 will remain after the prongs and arms are withdrawn from the fabric.

The base 4, the prongs 2 and the arms 3, as well as the arms 5 and 8 are each provided with reinforcing ribs 12 which greatly 20 add to the strength and rigidity of the device without materially adding to the bulk or weight thereof and thus greatly enlarging the field of serviceability. Thus, I have shown my novel device as supporting a portière or curtain 13, which is pierced or engaged by the prongs 2 and arms 3, while the doubled hook 7 engages a ring 14, which slides on a conventional curtain rod not shown. It will further be obvious that no 25 slipping or lateral movement of the device with respect to the curtain 13 is possible, since any tension, such as the weight of the curtain 13, exerted on the device, merely serves further to strengthen the engagement 30 of the prongs and arms 2 and 3 with the body of the curtain, the hook 7 being in turn prevented from being detached or working loose from the ring 14 or other object, either by its position as in Fig. 1, 35 or by the contacting locking humps or knobs 6 and 9.

In Fig. 6 I have shown a modified form of my invention wherein the prongs 2 are relatively thin throughout their entire 45 length and are provided with the swelled or enlarged portions 15 which serve to interlock with the elastic, contracting warp and weft of the fabric to prevent slipping. In this construction also, only a small, practically invisible hole remains after the prong 50 is withdrawn, since the cloth or fabric is only temporarily distended or parted wide enough to permit of the passage of the enlarged portion 15, after which the warp and weft adjust themselves around the relatively thin portions 16 of the prongs 2.

In Fig. 7 I have shown a further modified construction, wherein the prongs 2, of the modified construction shown in Figs. 1 60 and 6, are corrugated or waved as at 17, to afford a firmer engagement of the prongs with the fabric if so desired.

It will thus be seen that I have devised a novel fastening and supporting device 65 which is compact, neat and serviceable, and

one which can be manufactured economically by a single stamping or punching operation. It will also be seen that my novel fastener can be secured to a fabric or similar material without the use of stitches. 70

It will now be apparent that I have devised a novel and useful fastening and supporting device which embodies all the features of advantage enumerated as desirable in the statement of the invention and the 75 above description and while I have shown in the accompanying drawings forms thereof which are at present preferred by me since they will give in practice satisfactory and reliable results, it is to be understood 80 that such forms can be varied without departing from the scope of my invention or sacrificing any of its advantages.

Having thus described my invention, what I claim as new and desire to secure by Letters Patent is:

1. A fastening and supporting device comprising a doubled hook, converging, piercing prongs on either side of said hook, a base integral with and common to said hook and said prongs and forming a right angle therewith, each of said prongs being tapered and provided with a recessed portion at its juncture with said base, a pair of doubled arms integral with and extending 90 from either end of the opposite edge of said base in parallelism therewith, the free, pointed ends of said arms being juxtaposed and provided with recessed portions, and reinforcing ribs for said hook, prongs 95 and arms. 100

2. A fastening and supporting device comprising a doubled hook, parallel, piercing prongs on either side of said hook, a base integral with, and common to said hook and said prongs and forming a right angle therewith, each of said prongs being provided with an enlarged portion near its juncture with said base, a pair of doubled arms integral with and extending from either end of the opposite edge of said base in parallelism therewith, the free ends of said arms being juxtaposed and provided with recessed portions, and reinforcing ribs for said hook, prongs, base and arms. 110 115

3. A fastening and supporting device comprising a doubled hook, piercing prongs on either side of said hook, a base integral with and common to said prongs and hook and forming a right angle therewith, each of said prongs being corrugated and provided with a recessed portion at its juncture with said base, a pair of doubled arms integral with, and extending from either end of the opposite edge of said base in parallelism therewith, the free ends of said arms being juxtaposed and provided with recessed portions, and reinforcing ribs for said hook, prongs, base and arms. 120 125

4. A fastening and supporting device 120

comprising a doubled hook, piercing prongs on either side of said hook, a base integral with and common to said hook and said prongs and forming a right angle therewith, 5 each of said prongs being corrugated and provided with an enlarged portion at its juncture with said base, a pair of doubled

arms integral with and extending from either end of the opposite edge of said base in parallelism therewith, the free ends of 10 said arms being juxtaposed and provided with recessed portions, and reinforcing ribs for said hook, prongs, base and arms.

LILLIAN K. ENGLE.
